UNITED STATES PATENT OFFICE.

SAMUEL S. FULLER AND ROBERT SALVADGE, OF STRATFORD, ONTARIO,
CANADA.

AUTOMATIC CAR-BRAKE.

SPECIFICATION forming part of Letters Patent No. 288,127, dated October 2, 1883.

Application filed March 21, 1882. (No model.)

To all whom it may concern:

Be it known that we, SAMUEL S. FULLER and ROBERT SALVADGE, of Stratford, county of Perth, Province of Ontario, Canada, have 5 invented a new and useful Improvement in Automatic Car-Brakes; and we declare the following to be a full, clear, and exact description of the invention, such as will enable others skilled in the art to which it pertains to 10 make and use it, reference being had to the accompanying drawings, which form a part of this specification.

Our invention consists in the combinations of devices and appliances hereinafter specified, 15 and more particularly pointed out in the claims.

In the drawings, Figure 1 is a longitudinal section of the body of a car to which our invention is applied, showing the arrangement when the brakes are applied at one end only. 20 Fig. 2 is a plan view of a portion of a car to which our invention is applied, with flooring removed. Fig. 3 represents separate views of the mechanism by which the push-bar is thrown into or out of action. Fig. 4 represents 25 separate views of the pendent lever and lock-bolt. Fig. 5 represents separate views of the friction-wheel, winding-reel, ratchet-wheel, pawl, and hanger. Fig. 6 represents a separate view of the shaft with its system of 30 levers. Fig. 7 represents separate views of the friction-wheel upon the axle, showing the method of its construction. Fig. 8 represents 35 separate views of the bracket for suspending the friction-wheel, and the hanger for chain-pulley.

The object of our invention is, first, to provide an automatic car-brake for freight-trains which shall be made to operate by the power of reaction, or of the train's momentum, producing the compression of the draw-head, 40 whereby the brakes are applied when the speed of the train is checked by the engine or otherwise; second, to provide an automatic car-brake which may be easily applied to any car without in any manner interfering with the free use of the hand-brakes or with the backing of the train; third, to provide an automatic car-brake which may be applied to a car without requiring any new means of connec- 45

tion between cars, or any material alteration 50 of the ordinary construction of a car, thus permitting cars not equipped with this device to be made up in the same train with cars equipped therewith, without regard to their position in a train; fourth, to provide an automatic car-brake which may be thrown into or out of action from both sides of a train, or from the top, 55 allowing the use of a pushing-engine without setting the brakes; fifth, to provide an automatic car-brake which shall be instantly released on releasing the compression of the draw-head by the moving of the engine or otherwise; sixth, to provide an automatic brake 60 which may be operative at any speed at which the train is moving, and which may be applied 65 by setting the hand-brakes of a rear car when the train is backing.

In the annexed drawings, A is the floor of a car. A' represents the center stringers. A² is one of the outside stringers. A³ represents the truck-beams, and A⁴ represents a car-wheel. a is the axle of the truck. a² is a 70 brake. a³ is the brake-lever. A⁵ is a draw-head. A⁶ is a spring-plank. A⁷ is a brake-staff. a⁸ is the connection between the brake-staff and brake. These are ordinary parts in 75 the construction of cars.

In carrying out our invention, B is a pendent lever pivoted at its upper end to the center stringers, as shown at b, projecting freely 80 downward, and provided at its lower end with a friction-roller, b'. This pendent lever is preferably constructed of two bars, bent as shown in Figs. 1 and 4, the bars being kept suitably apart from each other by means of 85 wood riveted between them, or by any other proper means, as shown at b².

C is a push-bar pivoted to the pendent lever at the rear end, as shown at c, and preferably forked at the forward end, as shown at c' and c². The pivoted end of the bar is provided with means of adjustment to the lever B, as shown by c³, whereby the bar may be suitably adjusted behind the draw-head A⁵. The lower portion of this push-bar may be made straight, 95 or curved at its pivoted end.

D D represent an operating rod or rods passing from the side of the car through to

either side. In order to adjust it conveniently to the stringers A' and A'', we prefer that the middle portion should be a casting constructed with a central cranked section, d, and end sections, d', provided with square recesses or sleeves d'', into which the squared ends d' of the rods D D may be inserted. This casting is adapted to occupy the space between the center stringers, the rods D D being passed 10 through the stringers and connected with the sleeves d''.

d' represents cranked handles on the outer ends of the rods D D on either side of the car. This operating-rod is designed to be so adjusted to the stringers that the middle cranked section, d, shall rest under and support the forked end c' of the push-bar C, as shown at c'. The operating-rod thus furnishes means by which motion may be conveyed from either 15 side of the car to throw the push-bar into or out of action. When the push-bar is in its normal or acting position, the forked end c' rests directly back of the rear end of the draw-bar. By reversing either of the cranked handles d' d' the forward end of the push-bar will 20 be thrown up out of its normal position, as indicated by the dotted lines C'.

d'' is a bearing for the operating-rod attached to the exterior of either outside stringer, 30 provided with two lugs or stops, d'', which support the handle d' in the proper position when turned in either direction. To further insure that the operating-rod shall be held in the position in which it may be set, and be prevented from turning over when the car receives a shock, the bearing d'' is provided with 35 another segmental projection, d'', under which the handle is forced by the action of a spring, d'', secured upon the rod on the inside of the stringer. This spring also serves to prevent the rod D from working out of the sleeve d''. When it is desired to work the operating-rod D from the top of a box-car, said rod is provided at its outer end with a chain-pulley, e, 40 with a handle, e', attached, said pulley e and handle e' taking the place of one of the cranked handles d'.

e' is another pulley, secured to a cranked shaft, E, on the top of a car, said shaft supported by the standards e'' and e''' and extending within a few inches of the running-board. 50

e'' represents chains passing over and suitably secured to the pulleys e and e'', to prevent slipping, said chains being connected together by rods e''' on the side of the car.

F is a spring push-bar perforated with bolt-sockets at various places, as shown at f, for the purpose of adjustment. The forward end is inserted between the bars of the pendent 60 lever B and rests upon the friction-rollers b'. When applied to the car, the spring push-bar extends underneath the truck-beams A' and above the spring-plank A'', and is secured at its rear end to the bottom of the friction-wheel hanger G, as shown at f'.

F' is a push-spring encircling the bar F, and

is held in place between the washers f'' and f''' f''' being the point of resistance.

f'' is an angular-shaped lock-bolt constructed with a shank, f''. The sockets f are constructed to correspond with the shape of the lock-bolt, the construction of each being such that when the bolt is inserted in an inverted position in the socket and turned downward, it is effectually secured therein and serves to hold 75 the washers and bar in proper adjustment.

F'' is a reacting spring, also encircling the bar F, and held in position by the washer f'', and a bifurcated support, F'', secured to the spring-plank A'', allowing the bar F to pass 80 freely through.

G is a friction-wheel hanger pivoted at its upper end to a bracket, H, said bracket preferably a metal casting, and firmly secured to the inner truck-beam, A'', and provided at its 85 outer end with a bearing, h. The upper arm of the bracket is slotted longitudinally to allow of the proper adjustment of the bearing h and hanger G. The upper side of the bracket-arm and under plate of the bearing are preferably serrated on their adjacent faces, and interlock with each other, the under plate being provided with flanges to engage the arm of the bracket and prevent lateral movement. 90

G' is a friction-wheel pivoted in the hanger 95 G, preferably made of cast-iron.

G'' is a winding-reel provided with a ratchet-wheel, g, also pivoted in the hanger G.

g' represents one or more gravity-pawls, preferably three in number, pivoted to the 100 friction-wheel, as shown at g'', and adapted to engage with the ratchet-wheel g. It is important that these pawls should be limited in their movement when disengaged from the ratchet-wheel, so that they shall not be carried 105 too far from the point of contact with the ratchet-teeth. To this end the pawl is constructed with a heel, as shown at g'', adapted to come in contact with a stop, g'', on the spoke of the friction-wheel, which allows only sufficient 110 movement of the pawl to enable it to clear the ratchet-teeth.

G''' is the pivoting-shaft, provided with a shoulder, as shown at g''', abutting against the side of the hanger, the outer end of the shaft 115 secured by a split key, g'', inserted through it. The hubs of the friction-wheel G' and of the winding-reel G'' are preferably recessed, as shown at g''', permitting their being packed with waste, which, being saturated with oil, 120 retains the means of lubrication for a long season.

I is a friction-wheel mounted upon the inside axle of each set of trucks, constructed of segments I', of wood, paper, leather, or other 125 suitable material, bolted together. In case wood is used we prefer that the end grain of one segment should be matched against the side grain of the next segment, so as to break joints and bring end grain and side grain of 130 the wood to the surface in alternate layers. These segments are constructed with bolt-

holes which match each other, for the speedy adjustment of the bolts. In this way the wheel may be constructed upon the axle until sufficient breadth of face is obtained, as may be desired.

5 I^2 are metallic segments on either side the wheel I , which serve as tie-plates.

I^3 are outside metallic segments recessed to fit over and upon the tie-plates I^2 , thus preventing their separation when the keys are driven into the key-seats I^4 to secure the structure to the axle. The friction-wheel I being of softer material than the friction-wheel G' , and the latter being loosely pivoted in the hanger G , it is evident that when the two are brought together the wear will be generally and quite evenly distributed.

15 J is a bracket, preferably an iron casting, firmly secured to the under side of the center stringers, A^1 .

J' is a shaft pivoted in the arms j of the bracket J , with a lever-arm, J^2 , rigidly secured thereto.

20 J^3 and J^4 are additional lever-arms, loosely pivoted on the shaft J' .

25 J^5 is a collar rigidly secured to the shaft J' , constructed with shoulders j^6 and j^7 on opposite sides of the collar. The shoulder j^6 is constructed to abut against the lever J^3 and hold it in a horizontal position when the brake is free. j^6 and j^7 are springs encircling the shaft J' . One end of said springs is secured to the lever-arms J^3 and J^4 , as shown at j^8 and j^9 . The other ends of the springs are secured to the bracket J , as shown at j^7 and j^8 in Fig. 2. These springs are designed to return the levers J^3 and J^4 to their normal position when the brake is loosened; also, to assist in unwinding the brake-chain K , connected with the winding-reel G^2 and the outer end of the lever, and hold it taut when not in operation.

30 J^6 is a stop upon the bracket J , designed to check the arm J^2 when moved to the position indicated by the dotted lines J^6 .

35 It will be seen that the construction of the lever-arms J^2 , J^3 , and J^4 upon the shaft J' , and the supporting-collar J^5 , is such that the arm J^2 may be thrown up to the position indicated by the dotted lines J^6 without moving the other lever-arms. When the arm J^2 is pulled down to a perpendicular by the winding up of the chain K , the arm J^2 will be moved into the position of J^6 , while the arm J^4 will remain in position, and when the arm J^4 is brought down to a horizontal the arm J^2 will also be moved into the position of J^6 .

40 K^2 is an automatic brake-rod connected with the brake-lever a^3 and with the lever-arm J^2 by means of sockets k , arranged to permit of any desired adjustment of the rod.

45 K^3 is an automatic brake-rod supported by pulleys k^2 , connected with the outer end of the lever-arm J^4 and with the brake-chain K^4 upon a winding-reel attached to a friction-wheel 50 similar to G , with ratchet and pawl, as shown at L , adapted to press upon a wheel similar to

I , as shown at L^2 , by means of a push-bar and connecting mechanism like that already described.

The construction of the lever J^2 upon the shaft J' is such that its power is continually increasing to the end of its stroke, and is only prevented from becoming a dead-lock by the stop j^9 .

It is apparent that as the brakes are tightened the power increases, and when the lever J^2 is brought to its full stroke it is easily held in place, and no greater strain will be brought to bear on the brake. Any further strain caused will be expended in a direct pull upon the lever-arms J^3 and J^4 , as the case may be. By this arrangement the slipping of wheels by too-great compression of the brakes is prevented.

55 In the use of this device, if the car is moving in the direction of the arrows, it will be seen that when the draw-head A^5 is forced back upon the push-bar C by checking the speed of the engine or otherwise, the lower end of the lever B is forced back with the spring push-bar F and lower end of the hanger G , bringing the friction-wheel G' into contact with the friction-wheel I upon the axle of the truck with a power proportionate to the rearward movement of the push-bar C and 60 the compression of the springs F' and F^2 . The friction-wheel G will thus be caused to rotate in the direction indicated by the arrows, and also the winding-reel G^2 , winding up the chain K , by which means the lever-arm J^3 is 65 pulled downward and the lever-arm J^2 is thrown back into the position indicated by the dotted lines J^6 , thereby pulling the brake-lever back by means of the brake-rod K^2 and applying the brakes.

70 It is evident that by this mechanism the brakes will remain applied while the compression of the draw-head A^5 is maintained upon the push-bar C . It is also evident that when this compression is removed from the push-bar C the springs F' and F^2 , assisted by springs j^6 and j^7 , will instantly throw the brakes out of action before the car begins to move, which is an important feature of this invention.

75 It has been assumed thus far that the mechanism has been operated from the forward end by the compression of the forward draw-bar.

The necessity of working the automatic 80 brakes from the forward end of the car is apparent from the fact that otherwise, should the brakes be set through the compression of the rear draw-bar, the car would have to be started with the brakes set before the compression of the draw-bar could be relieved and the brakes loosened. For this reason it is necessary that both ends of the car should be equipped with the automatic brake appliances, both operating on the same set of brakes.

85 In backing a train it will be seen that while the draw-heads will be compressed the wheels

and axles will revolve in an opposite direction, as also the friction-wheel G' . The pawls will then glide over the ratchet-teeth, the winding-reel will remain at rest, the chain K will not be wound up, and hence the brakes will not be applied. When the car is running in an opposite direction from that described, the brakes will be applied in the same manner by revolving the operating-rod at each end of the car, for when one set of automatic devices is in use the other will not be.

By means of the operating-rod the action of the brakes can be suspended when a pusher-engine is used in starting a train, and then from the top or either side of the car they may be thrown into position for action.

It is observed that the handles of the operating-rod are always to be turned in the direction in which the car is running to apply the brakes, and when the operating-rod on each end of the car are turned toward the center of the car the automatic brakes will be rendered inoperative.

In case double brakes are desired to be used on a single car, the system of levers on shaft J' will be required to be connected with the evener in common use in hand-brakes.

It is evident that the system of levers on shaft J' could be dispensed with, and the winding-chains K and K' could be connected to an ordinary evener; but such a connection would involve more frictional power and tend to cause the wheels to slip.

It is furthermore evident that two friction-wheels might be used in each hanger instead of one.

The operating-rod D also can be made all in one piece, and secured to the car by suitable supports.

40. What we claim is—

1. The combination, with a movable draw-bar, of the pivoted push-bar, forked at its outer end, the rock-shaft having a cranked portion arranged in the forked end of the push-bar for swinging the latter, and mechanism connecting the push-bar with the brakes, substantially as and for the purpose described.

2. The combination, with a movable draw-bar, of the pendent lever B , a push-bar, C , having a forked outer end and pivoted to the lever, a rock-shaft, D , having a cranked portion arranged in the forked end of the push-bar, and devices connecting the lever with the brakes, substantially as described.

55. 3. The combination of a pivoted lever, B , a push-bar, C , connected at one end with the lever, and having its other end capable of being moved into and out of line with a movable draw-bar, a swinging hanger, G , carrying a friction-wheel, G' , and a winding-drum, G'' , a yielding connection between the hanger and the pivoted lever, mechanism connecting the winding-drum and the brakes, pawls mounted on the friction-wheel, and a ratchet on the winding-drum, substantially as described.

60. 4. The combination of a pivoted lever, B ,

a push-bar, C , arranged to receive the thrust of a draw-bar, a swinging hanger, G , carrying a friction-wheel, G' , and a winding-drum, G'' , a bar, F , connecting the lever and the hanger, and carrying a push-spring, F' , and reacting spring, F'' , a shaft, J' , having a rigidly-attached lever-arm, J^2 , lever arms J^3 and J^4 , loose on the said shaft, a connection, K^2 , between the lever-arm J^3 and the brake-lever a^3 , and connecting mechanism between the lever-arm J^4 and a second swinging hanger carrying a friction-wheel and winding-drum, substantially as described.

5. The combination, with the push-bar and depending lever B , and the bar G , supporting the bearing of the winding-drum and friction-wheel, of the bar F , having one end connected to said bar G and the other end in sliding connection with said depending lever, and the spring F' , surrounding said bar F , and having one end supported by a fixed stop carried by said bar, and the other end bearing against the loose shoe f^2 , substantially as described.

6. The combination, with the push-bar and depending lever B , and the drum and friction-wheel supporting pivoted arm G , of the connecting-bar F , the spring F' , arranged between a stop on said bar and the depending lever, and the spring F'' , arranged between a stop on said bar and an independently-supported stationary stop, and arranged to move the bar F in an opposite direction to the thrust of the push-bar, substantially as described.

7. The connecting-bar F , having the bolt-holes, and notches or recesses in the upper edges of their walls, in combination with the locking-bolts f^4 , having an arm bent at an angle, and provided with a shank, f^5 , which will be held out of coincidence with the notch or recess of a bolt-hole when the bent arm hangs freely, substantially as described.

8. In an automatic car-brake, the shaft J' , pivoted in a suitable bracket and provided with a fixed lever-arm, J^2 , the loosely-pivoted arms J^3 and J^4 , the rigid collar J^5 , with shoulders j and j' , and springs j^2 and j^3 , for communicating power to the brakes from the friction-wheels, substantially as described.

9. The combination, with the operating-rod and its cranks, of lugs or strips d^6 , segmental projections d^7 , and spring d^8 , whereby the rod is locked in either position, substantially as described.

10. In an automatic car-brake, the operating-rod, said rod provided at its outer end with a pulley and crank-handle, in combination with a cranked rod and pulley secured upon the top of the car, and connected with the lower pulley by means of a suitable band, substantially as described.

11. The combination of a pendent lever, B , a push-bar, C , connected at one end with said lever, and having a free end capable of adjustment into and out of line with a draw-bar, a pivoted swinging hanger, G , mechanism con-

necting the hanger with the pendent lever, a friction-wheel, G' , and winding-drum G^2 , mounted on the hanger devices connecting the drum with the brakes, and a friction-wheel, 5 I, on the car-axle, consisting of segmental sections I', arranged side by side and tied together, substantially as and for the purpose described.

In testimony whereof we sign this specification in the presence of two witnesses.
